* cited by examiner

Primary Examiner—T. Chase Nelson*Assistant Examiner*—Michael A Pratt*(74) Attorney, Agent, or Firm*—David D. Winters(57) **CLAIM**

The ornamental design for “serrated sabot,” as shown and described.

DESCRIPTION

FIG. 1 is a perspective view of the serrated sabot from the top; FIG. 2 is a front elevation view of the serrated sabot, the back view, the left side view, and the right side view being mirror images thereof;

FIG. 3 is a top plan view of the serrated sabot

FIG. 4 is a bottom plan view of the serrated sabot; and,

FIG. 5 is another perspective view of the serrated sabot from the bottom.

The broken lines in FIG. 1, FIG. 3, and FIG. 5 are included for the purpose of illustrating environment and form no part of the claimed design.
